UNITED STATES PATENT OFFICE

2,498,166

FOUNTAIN PEN

Fred Yoshiharu Kuriyama, Honolulu,
Territory of Hawaii

Application September 21, 1946, Serial No. 698,455

3 Claims. (Cl. 120—42.03)

1

My invention relates to improvements in fountain pens.

The primary object of the invention is to provide a fountain pen with simply constructed, inexpensive means operative by a finger of a hand grasping the pen to either house the pen point for protection purposes, or, expose said pen point for writing purposes.

Another object is to provide a fountain pen with means of the character and for the purpose above set forth which is operative by easy, light pressure on the pen clip.

To the accomplishment of the above and subordinate objects appearing, a preferred embodiment of my invention has been illustrated in the accompanying drawing, set forth in detail in the succeeding description, and defined in the claims appended thereto.

In said drawings:

Figure 1 is a view in perspective illustrating the manner in which the clip-forming bar, outer and inner caps, and spreader member may be detached as a unit from the pen barrel.

Figure 2 is a fragmentary view partly in longitudinal section and partly in side elevation drawn to an enlarged scale and illustrating the parts in normal position with the inner cap housing the pen point.

Figure 3 is a similar view with the parts in the rearward limit of movement thereof and the sections of the inner cap opened to expose the pen point.

Figure 4 is a view in perspective of the parts disassembled.

Figure 5 is a fragmentary view in plan drawn to a smaller scale.

Figure 6 is a fragmentary view in transverse section drawn to a larger scale and illustrating the manner in which the sections of the inner cap are hinged.

Referring to the drawing by numerals, according to my invention a fountain pen is provided comprising a barrel 1 having a slightly reduced, externally threaded, front end section 2 fixed therein, in any suitable manner, with a cylindrical, reduced neck 3 extending forwardly therefrom along the axis of the barrel 1 and in which the usual pen point 4 is suitably fixed, together with the usual ink feeder bar 5.

An outer cap 6 having the form of a flat nosed bullet is threaded onto the front section 2, and which is open at the front end 7 thereof, and extends forwardly of the neck 3, but with the pen point 4 and feed bar 5 extending out of said front end thereof in the axis of the same. The 55

2

outer cap 6 is provided in one side thereof with a longitudinal slot 8 extending from the rear end of said cap to a central cross slot 9 in said cap into which the front end of the slot 8 opens in the center thereof. An internal, annular shoulder 10 is provided in the outer cap 6 adjacent the rear end thereof and spaced forwardly of the section 2 for a purpose presently clear.

An inner cap 11 of forwardly tapering form, with a rounded front end 12, is provided in the outer cap 6 to be slid endwise forwardly and rearwardly into and out of the front end 7 of said cap 6, respectively. The inner cap 11 is split longitudinally into a pair of half sections 13, 14 adapted to mate side by side, in edge-to-edge closed relation, and which are hinged at the rear ends thereof, and at confronting side edges on one side of the cap, by pins 15, to the front end of a rearwardly extending spring bar 16. The spring bar 16 is provided with an out-turned, right-angled, rear end 17 formed with a reduced terminal 18 adapted to extend out of the outer cap 6 through the slots 8, 9 and to slidably fit in the slot 9. The rear end 17 inwardly of the terminal 18 is wider than the slot 8 and designed to extend through the slot 9 and block sliding of the terminal 18 out of the slot 9 into the front end of said slot 8, and is also designed to snap behind the shoulder 10, all for a purpose presently seen.

A clip-forming bar 19 is fixed, in any suitable manner, adjacent its front end, on the terminal 18 at a right angle to said end 17 to extend alongside the outer cap 6 and barrel 1 with its front end portion normally spaced from the outer cap 6 by the spring bar 16.

A tubular spreader member 20 surrounds the neck 3, within the outer cap 6, with a rear, annular flange 21 of right angled cross section 40 clamped between the shoulder 10 and the front end section 2 of the barrel 1, and which fits part way into the inner cap 11 with an outer end, external, circumferential flange 22 flush with the front end 7 of the outer cap 6. The spreader member 20 has a tapered front end portion 23, and the inner cap 11 slides forwardly and rearwardly on said portion 23 and on the flange 22. In the rearward sliding movement of the inner cap 11, the sections 13, 14 thereof are spread 45 apart by said portion 23 and the flange 22. This spreading apart or opening of the sections 13, 14 occurs as the inner cap 11 is moved rearwardly from a normal forward position presently explained.

Referring now to the use and operation of the

described invention, in the normal position of the parts, the clip-forming bar 19 is in a forward position with the end 17 of the spring bar 16, and the terminal 18 thereof projecting through and out of the cross slot 9, and the inner cap 11 shoved forwardly and projecting part way out of the front end 7 of the outer cap 6 with the sections 13, 14 wedged closed by said end 7 and said cap member 11 completely housing the pen point 4, all as shown in Figure 2. In this position of the parts, the rear end 17 of the spring bar 16 extends across the front end of the slot 9 and prevents rearward movement of the inner cap 11 so that said cap is locked in the described normal position thereof in which the pen point 4 is completely housed. Now, by pressing the clip-forming bar 19, inwardly, in opposition to the spring bar 16, by means of a finger of a hand holding the pen, said end 17 may be moved from in front of the slot 8 to unlock the inner cap 11, after which the clip-forming bar 19 may be moved rearwardly by said finger with the terminal 18 of the spring bar 16 sliding in the slot 8 into a normal limit of movement established by engagement of said end 17 of the spring bar 16 with the flange 21 of the spreader member 20. Thus, the inner cap 11 may be slid rearwardly into a corresponding limit of rearward movement. In such rearward movement of the inner cap 11, the sections 13, 14 are spread open by the spreader member 20 to expose the writing portion of the pen point 4. In the rearward limit of movement of the clip-forming bar 19, and the spring bar 16, the end 17 of said bar 16 snaps behind the flange 10 and locks the parts in the rearward limit of movement thereof and with the sections 13, 14 open and the pen point 4 exposed and extending forwardly of the front end 12 of said inner cap 11. The clip-forming bar 19 may be used in the usual manner, as will be clear. As shown in Figure 1, by unscrewing the outer cap 6 from the section 2, the clip-forming bar 19, inner cap 11, and spreader member 20 may be detached, as a unit therewith to permit the pen point 4 and front end of the barrel 1 to be dipped in ink for filling of the barrel in the usual manner.

The foregoing will, it is believed, suffice to impart a clear understanding of my invention, without further explanation.

Manifestly, the invention, as described, is susceptible of modification, without departing from the inventive concept, and right is herein reserved to such modifications as fall within the scope of the appended claims.

What I claim is:

1. A fountain pen comprising a barrel, a reduced neck on the front end of the barrel, a pen point extending forwardly from said neck, an outer cap on the front end of the barrel enclosing said neck and having an open front end out of which said pen point extends, a tubular spreader member in the outer cap, an inner cap slidable on said spreader forwardly and rearwardly therein, said inner cap comprising hinged together sections swingable into closed relation during forward movement of the inner cap to house said pen point, and being swingable into

open position during rearward movement of said inner cap to expose said pen point, said spreader being tapered to swing said sections open during rearward movement of the inner cap, said front end of the outer cap acting to swing said sections closed during forward movement of said inner cap, and manipulative means for moving said inner cap.

2. A fountain pen comprising a barrel, a reduced neck on the front end of the barrel, a pen point extending forwardly from said neck, an outer cap on the front end of the barrel enclosing said neck and having an open front end out of which said pen point extends, a tubular spreader member in the outer cap, an inner cap slidable on said spreader forwardly and rearwardly therein, said inner cap comprising hinged together sections swingable into closed relation during forward movement of the inner cap to house said pen point, and being swingable into open position during rearward movement of said inner cap to expose said pen point, said spreader being tapered to swing said sections open during rearward movement of the inner cap, said front end of the outer cap acting to swing said sections closed during forward movement of said inner cap, and manipulative means for moving said inner cap comprising a bar endwise movable along said barrel and connected to said inner cap.

3. A fountain pen comprising a barrel, a reduced neck on the front end of the barrel, a pen point extending forwardly from said neck, an outer cap on the front end of the barrel enclosing said neck and having an open front end out of which said pen point extends, a tubular spreader member in the outer cap, an inner cap slidable on said spreader forwardly and rearwardly therein, said inner cap comprising hinged together sections swingable into closed relation during forward movement of the inner cap to house said pen point, and being swingable into open position during rearward movement of said inner cap to expose said pen point, said spreader being tapered to swing said sections open during rearward movement of the inner cap, said front end of the outer cap acting to swing said sections closed during forward movement of said inner cap, and manipulative means for moving said inner cap comprising a clip-forming bar endwise movable, said bar and outer cap embodying coacting devices for locking said bar against endwise movement.

FRED YOSHIHARU KURIYAMA.
